UNITED STATES PATENT OFFICE.

ORMOND EDGAR WALL, OF HONOLULU, TERRITORY OF HAWAII.

TOY BOAT.

1,318,623.

Specification of Letters Patent.

Patented Oct. 14, 1919.

Application filed March 14, 1919. Serial No. 282,692.

To all whom it may concern:

Be it known that I, ORMOND E. WALL, a citizen of the United States, and a resident of Honolulu, Territory of Hawaii, have invented certain new and useful Improvements in Toy Boats, of which the following is a specification.

My invention is an improvement in toy boats, and has for its object to provide a boat of the character specified and of the submarine type, wherein propelling mechanism is provided, and approximately horizontal vanes or rubbers are provided for causing the boat to dive or rise in the water, wherein the propeller is spring controlled, and the vanes are controlled by the same spring as that which controls the propeller, permitting them to move into rising position.

A further object of my invention is to provide a spring controlled gun or torpedo tube, and means for normally restraining the action of the spring controlled by the tensioning and relaxing of the spring.

A further object of the invention is to provide means for placing the spring under tension outside of the boat, which is controlled by other mechanism mounted on the boat laterally and is arranged to be swung into operative position when the rudder is swung laterally into inoperative position at approximate right angles to the axis of the boat and to be released from the spring winding mechanism when the rudder is in operative position.

In the drawings:

Figure 1 is a top plan view of the improved boat;

Fig. 2 is a side view, showing the boat in diving or an operative position;

Fig. 3 is a longitudinal vertical section; Figs. 4 and 5 are sections on the lines 4-4 and 5-5, respectively, of Fig. 3, each view looking in the direction of the arrows adjacent the line;

Fig. 6 is a view similar to Fig. 4, showing the parts in another position;

Fig. 7 is a perspective view of the vanes and their connection.

In the present embodiment of the invention, a boat is provided, of the submarine type, and consisting of a lower section 1 and an upper section 2, the said sections being detachably connected by means of the tapering ferrule 3 at the rear, which is connected with the section 1 and into which the rear end of the other section 3 may be thrust to clamp the sections together at the rear end. At the front end the sections are connected by an angle bolt 4, which is connected through a slot 5 extending longitudinally of the upper section. It will be evident that when the section 2 is pushed forwardly with respect to the section 1, the angular portion of the bolt will come into register with the slot, and the front end of the upper section may be lifted away from the lower section sufficiently far to release the bolt 4, after which the rear end of the upper section may be withdrawn from the ferrule.

The lower section carries on its under surface and intermediate its ends a center board 6, and the upper section carries on its upper surface and intermediate its ends a superstructure 7. Vertical rudders 8 for assisting in guiding the boat laterally are arranged at each end of the superstructure, being pivotally connected therewith, and each rudder has an angular arm 9 at its inner end, the arms extending in opposite directions. These arms are connected by a link 10 which is pivotally connected to each arm in such manner that the rudders will be simultaneously swung in the same direction when the link is moved longitudinally, that is, when one rudder at the left of Fig. 1 is swung upwardly, that at the right of Fig. 1 will also be swung upwardly. This link passes between the periscopes 11 of the submarine, as shown in Figs. 1 and 2.

A spring gun or torpedo tube 12 is mounted on the upper surface of the submarine, the said gun pointing forwardly, and a projectile 13 is adapted to be held within the gun and to be shot therefrom. The ejection of the projectile is controlled by a spring 14.

arranged between the projectile and the closed end of the tube, and it will be noticed that the outer end of the projectile is reduced.

5 A pin 15 is mounted to slide vertically through the upper section of the vessel and through the under side of the barrel and to engage in front of the shoulder formed between the body of the projectile and reduced portion, to prevent the ejection of the projectile under the influence of the spring.

The pin is normally pressed downward by a spring 16, and a plate 17 is connected to the lower end of the pin. This plate is 15 guided vertically by means of a guide pin 18 which is held in the upper section of the boat and has a head at its lower end, the pin passing through an opening in the plate.

20 The propeller 19 of the boat is secured to a propeller shaft 20 which is journaled at the stern of the boat, and the propeller is driven by means of a spring 21 which, in the present instance, is a rubber band or bands, 25 which may be twisted together to drive the propeller. These bands are connected at one end to the propeller shaft 20 and at the other to a link 22 which, at its forward end, is connected to a laterally offset portion or 30 crank 23 on a shaft 24 journaled transversely of the boat near the forward end thereof. The link 22 has a lug 25 which, when the spring 21 is under tension, will engage the plate 17 as shown in Figs. 3 and 4, and will 35 hold the plate lifted, to hold the pin 15 in operative position to prevent ejection of the projectile.

As soon as the tension is relaxed the link 22 will be lowered, as will also the lug 25, 40 and the projectile will be released. Wings or vanes 26 are secured to the ends of the shaft 24, and these wings or vanes are so arranged that when the spring is under tension they will be held inclining upwardly to- 45 ward the stern of the boat, as shown in Fig. 2, to constrain the boat to dive and to hold it under water. As soon as the tension of the spring is relaxed, however, the vanes will not be held rigidly against the action 50 of the water but will swing to permit the boat to rise to the surface. The spring is placed under tension by means of a crank 27 journaled in the rudder 28 which guides the boat horizontally. This crank has se- 55 cured thereto a gear wheel 29 which is adapted to mesh with a pinion 30 on the propeller shaft, when the rudder is swung with its plane at right angles to the propeller shaft. The rudder is supported by a 60 frame 31 upon which it is journaled to swing laterally to permit the turning of the propeller shaft on the winding of the spring. The upper section 2 of the boat has openings 32 for admitting water to the in- 65 terior of the hull.

In use, when it is desired to put the spring under tension the rudder 28 is turned with its plane at right angles to the long axis of the boat, and by turning the crank the spring will be placed under tension. The 70 wings or vanes 26 will also be arranged, by the tension of the spring, to cause the boat to dive, and as soon as it is placed in the water it will be driven forwardly by the propeller and will dive beneath the surface. As 75 soon as the tension of the spring is relaxed to a sufficient degree the projectile will be released. The swinging of the rudder into normal position disengages the gear wheel 29 from the pinion 30 and permits the propeller to function under the influence of the 80 spring.

I claim:

1. A boat having a propeller at one end, a spring extending longitudinally of the 85 boat and connected to the propeller at one end for rotating the same, a spring gun on the boat, a pin extending into the barrel of the gun for engaging a projectile to hold the spring under tension, said pin being en- 90 gaged at its lower end by the spring to hold the same in proper position when the spring is tensioned and to release the projectile when the spring is relaxed, horizontal guiding rudders at the opposite sides of the boat, 95 a shaft to which the rudders are connected, said shaft having a crank within the boat and that end of the spring remote from the propeller being connected to the crank to hold the rudders in diving position when the 100 spring is under tension.

2. A boat having a propeller, a spring for driving the propeller; means for tensioning the spring, a crank shaft journaled trans- 105 versely of the boat near the bow thereof and having radial vanes at its ends at each side of the boat, the spring of the propeller being connected at one end to the crank of the crank shaft to hold the rudders in diving position when the spring is under tension. 110

3. A boat having a propeller, a spring for driving the propeller, horizontal guiding vanes on opposite sides of the boat and rigidly connected, and means in connection 115 with the vanes and controlled by the tensioning of the spring for moving the vanes into diving position and for holding them in such position until the tension of the spring relaxes.

4. A boat having a spring controlled prop- 120 eller, diving vanes in connection with the boat, and a connection between the spring of the propeller and the vanes for moving the said vanes into diving position when the spring is under tension and for holding them in such position until the tension of the spring relaxes.

5. A boat having a propeller, a shaft on which the propeller is journaled, a spring for driving the shaft, a rudder mounted to 130

swing on a vertical axis at the stern of the boat, a gear wheel having a crank journaled on the rudder, a pinion on the propeller shaft, the gear wheel being arranged to engage the pinion when the rudder is swung at right angles to the axis of the boat.

5 6. A boat having a spring controlled pro-

peller and driving vanes for constraining the boat to dive and controlled by the tension of the spring to diving position and by 10 the relaxing of the spring to elevating position.
